ACCORDION FOLD END-CLOSURE MEANS
FOR FLEXIBLE POCKET RECEPTACLESDouglas J. Broughton, Springfield, Mass., assignor
to Buxton, Incorporated, Springfield, Mass., a
corporation of Massachusetts

Application September 26, 1945, Serial No. 618,752

1 Claim. (Cl. 150—39)

1

This invention relates to an improvement in flexible pocket receptacles such as pass cases and the like and more particularly to an improvement in the means for binding or connecting the several transparent holders or "envelopes" in which pass cards, photographs or similar articles are displayed.

One object of my invention is to provide means for this purpose which will provide a more secure and efficient binding together of the holders.

A further object is to provide a structure in which a free and uniform hinging action is afforded the holders irrespective of the number which are bound together.

Another object is to provide a controlled degree of expansion across the back of the binding transversely of the axis of the hinges.

A still further object is to provide a binding which is adaptable to a wide range of pass case constructions.

Other and further objects and advantages will be made apparent in the following specification and claim.

In the accompanying drawings which illustrate embodiments of my invention,

Fig. 1 is a generally perspective view, parts being broken away, of a pass case embodying the invention;

Fig. 2 is a fragmentary generally perspective view of the binding member;

Fig. 3 is a generally perspective view showing a suitable form of holder or envelope member;

Fig. 4 is a fragmentary side edge elevational view showing the character of the expansion permitted by the binder;

Fig. 5 is a fragmentary side edge elevational view showing a modified form;

Fig. 6 is a fragmentary generally perspective view showing an alternative binder arrangement;

Fig. 7 is a fragmentary side edge elevational view showing a modified cover arrangement;

Fig. 8 is a detail side edge elevational view, parts being broken away, showing an alternative form of holder and the manner of attaching it to the binder element;

Fig. 9 is a detailed side elevational view showing a modified holder and its manner of connection to the binder element;

Fig. 10 is a fragmentary generally perspective view showing the invention embodied in a case having the holders hinged along one of their long sides; and

Fig. 11 is a generally perspective view showing the invention integrated with billfold structure.

It will be understood that for the sake of clear-

2

ness the thickness of the parts has been substantially exaggerated.

Referring to the drawings, 1 designates the holders, which are formed of any suitable transparent material such as regenerated cellulose or a suitable acetate or commercial plastic. The holders are in the shape of a flattened tube, one usual form, as shown in Fig. 3, being made by folding a sheet of the transparent material, and overlapping the edge portions as at 2 to form a flattened tube open at each end.

The binding member, generally indicated at 3 comprises a thin piece of leather, cloth or other suitable material provided with a plurality of accordion folds 4. One open end of the tubular holders is telescoped onto the folds 4 as clearly shown in Fig. 1, the inner face of the side walls of the holders being cemented to the outer faces of the folds. Preferably the holders extend only 10 part way down the folds, leaving free loop portions 5 beyond the ends of the holders. As shown in Fig. 4, loops 5 permit a limited degree of separation of the holders as indicated at 6 to provide easy turning of the holders and to assure 15 that the holders will lie flat when they are turned on their hinges. The degree of expansion of the binder can be nicely predetermined by the extent to which the holders are telescoped on the folds 4 and hence the depth of the loops 5 left at the 20 bound ends of the holders. In practice the loops 25 5 will ordinarily be relatively small, but they can be sized to meet constructional needs.

As shown in Fig. 1, the ends of the binding member 3 may be extended to form covers 7, one 30 of the covers 7 being further extended to provide a closure flap 8 which is releasably attached to the other cover by a snap fastener 9 or other suitable means.

Pass cases constructed according to my invention 40 are particularly well adapted for association with billfolds. The pass case may be attached to the billfold in any suitable manner. For example in Fig. 5 the end extensions of the binder 3 are made relatively short as indicated at 10 and 45 these extensions are cemented or otherwise secured to stiffly flexible members 11 formed of plastic or the like. The members 11 are adapted to be inserted in the opposed side pockets of a billfold in a well known manner to hold the case 50 within the billfold.

A modified form of the binder is shown in Fig. 6. There a plurality of relatively narrow strips 12 of thin leather or the like are provided with accordion folds 4 and the holders 1 telescoped and cemented thereon all as previously described.

The ends of the strips 12 are cemented or otherwise secured to cover members 13.

My construction lends itself to a wide range of cover construction. Thus if desired short end extensions 14 of the binder may be cemented to cover boards 15 which are covered with a suitably ornamented cover 16 including a "book back" 17.

In the forms so far discussed the cards or the like are inserted through the open outer ends of the tubular holder. If desired, however, the outer end of the holder may be closed as by a binding strip 18 and the base of the holder cemented to only one side of the fold 4 of the binder as indicated at 19 in Fig. 8, the other wall of the holder being left free of attachment to the fold leaving an opening through which cards or the like may be inserted in the holder. This arrangement affords greater security for the contents of the holder.

In Fig. 9 I have shown a modified form of holder in which the side edges of the holder are cut away as at 20 to form extensions 21. The extent of the cuts 20 is such that the extensions 21 extend to the bottom of loops 5. Expansion can take place at the binding as previously described due to the flexibility of the extensions 21 as indicated at the right of Fig. 9. The presence of the extensions 21 tends to restrict the freedom or ease of expansion, which is in some cases desirable, and the extensions 21 facilitate the assembly of the holders on the accordion folds since the holders are telescoped onto the folds until stopped by the engagement of the ends of the extensions with the bottom of the folds, the length of the extensions measuring the degree of binder expansion without requiring careful positioning of the holders to secure the desired size of the loops 5.

In some cases it is desired to have the holders hinged along one of their long sides instead of at one end. In the forms previously described this could be accomplished by changing the dimensions of the holders and binders. In Fig. 10 my invention is shown embodied in a side bound pass case using a modified form of holder. As there shown, the holders are formed of sheets of suitable transparent material 22 folded at 23, the edges opposite the fold being cemented one to each side of a binder fold 4 as indicated at 24 to form tubular holders 25 for the reception of cards or the like. The portions of the several folds 4 within the holders are cemented or otherwise secured together as at 26 to prevent the bound edges of the holders from spreading. If desired one end of the holders may be closed by a strip of adhesive tape or the like 27. It will be

understood that the invention is not limited to any particular form or number of holders.

As shown in Fig. 11, the invention may be employed to hinge one or more holders directly to any suitable element of the billfold. By way of example, as shown in the latter figure, one edge of the billfold panel 28 may be extended to provide the binding folds 29 on which holders 1 are telescoped as previously described, the end portions of the extension being folded up and cemented to the end holder as shown at 30.

What I claim is:

A pass case which comprises front and rear cover sections, a hinge section intermediate the cover sections and a section extending from the rear cover section, all made up as a continuous strip; the hinge section being formed with a plurality of accordion folds extending inwardly between the cover sections, a plurality of transparent flat tubular members open at both ends secured one on each of said inwardly extending accordion folds in telescopic relation therewith, said folds extending a short distance inwardly of the tubular members and holding the walls of the member carried thereby in spaced relation for the reception of pass cards and the like insertable through the opposite open end of the tubular member, a portion of said folds being positioned outwardly of said members to form small free loops between adjacent members to freely hinge the members to each other and to the front and rear cover sections of the strip, the said section extending from the rear cover section being foldable around the outer ends of the tubular members and into overlapping relation with the front cover section, and means to releasably connect said overlapping portion of the extending section to the front cover section.
